THERMOSTATIC RADIATOR ADMISSION
VALVE

Edward S. Halsey, North Miami, Fla.

Application June 16, 1932, Serial No. 617,592

10 Claims. (Cl. 236—42)

My invention relates to thermostatically actuated admission valve units for radiators, particularly for hot fluid heating systems in which the device is directly associated with the radiator 5 to be controlled.

The invention consists in the features and combinations and arrangement of parts hereinafter described and particularly pointed out in the claims.

In carrying out my invention I have sought to provide a valve controlling mechanism capable of automatic operation according to room temperature, capable of operation by hand and capable of adjustment to various temperatures, in 10 which the elements will be few, of economic construction, susceptible of ready and quick assembly, and in which elements perform plural functions in respect to automatic manual and adjustment operations. And further, to provide in 15 one single body design a product universally and conveniently adaptable to the requirements of any and all kinds of modern radiator installation, including the numerous types of concealed or covered radiation; connectable at top or bottom 20 and adapted to straight, angular, left, right or corner connections, with close or distant actuating bulbs, and with an adjusting dial and handle readily pointed in any desired direction and extendable to any desired extent, thereby 25 greatly reducing present manufacturing and distributing complication and expense; also a valve adaptable to all types of hot fluid heating systems. Further, my present device is conveniently 30 adaptable to the various types of installations indicated, without objectionable protrusion beyond the outline and projection of the radiator and its supply pipe, and the inherently light bulb portion is further shielded against injury by its 35 surrounding and securely anchored stack.

In the drawings:

Fig. 1 is the side elevation of one of these thermostatic controls, mainly in cross-section, with the center portion of its pendant expansion bulb and draft stack broken out.

Fig. 2 is a plan view of the bulb and stack, shown with its ventilated cover removed, and an end fraction of the attached valve.

Fig. 3 is a central cross-section of the valve body on line 3—3 of Fig. 1.

Figs. 4, 5, and 6 are respectively, side, back and top views, mainly in cross-section, of a specially devised close coupled swivel, angle, union coupling adapted to the valve body, accomplishing a 55 universal angle unit.

Fig. 7 is a front elevation of the valve bonnet showing adjusting dial and handle.

Fig. 8 is a side view in partial section of a modification of the valve cone.

Fig. 9 is a front elevation of one manner of 5 application of the device shown in Fig. 1, to a radiator.

Fig. 10 shows a similar installation but with the expansion bulb extended and attached to the wall beneath the radiator instead of the draft 10 stack.

Fig. 11 shows a front elevation of a stack installation of the device, alternative from that of Fig. 9, showing the adjusting dial and handle directed upward and indicating an extension stem 15 for covered radiators.

Fig. 12 is a front elevation of a bottom connected stack installation.

Fig. 13 is a plan view of the wire lock-ring for the swivel valve connecting unit shown by 20 Figs. 4, 5 and 6.

In the drawings, R, indicates the radiator; S, the supply pipe; 1, the valve body; V, the valve closure cone; 3, the actuating diaphragm bellows, and 2, its surrounding shield or stack.

Briefly stated, the heat flow to the radiator is modulated or cut off by the inward thrust of the bellows pushing the valve cone towards its seat by the hydraulic force of expansion of the liquid in the bulb, resultant from a rise in room temperature.

The temperature at which this automatic action occurs may be regulated by a turning adjustment of the external handle; and by turning this handle to its stop limit the heat can be 35 cut off completely, regardless of room temperature.

More in detail, the steam to the radiator is controlled by the axial movement of the valve piece, V, resultant from the expansion and contraction of the liquid in bulb, B, acting upon the metal bellows, 3, through the medium of the small connecting tube, 4. These hydraulic movements are conveyed to the valve, V, through the medium of push rod 3' and the heavily spring loaded sliding abutment unit, which carries said valve cone by means of a coarse threaded adjusting head, 5', and the closing thrust of the valve is resisted and retrieved by the coil spring, 6, stepped in the cup, 7, bearing on the collar of the revolving valve stem, 8. The outer end of this valve stem is squared and has a free sliding movement in the guiding handle shaft, 9, which is rotatable by the exterior handle, 10, and this rotating handle shaft makes a fluid 50 55

tight joint in the bonnet by means of a heavy outward spring thrust from the dial plate, 11, which is made of spring metal, formed with an outward dished center, so that when sprung 5 firmly back into the flat position shown, by lock nuts, 12, and 12', its inner beveled shoulder firmly presses a suitable plastic packing ring, 13, located between it and the counter-bored recess of the bonnet hub which acts as a journal for this 10 rotatable handle shaft.

It should be noted that the axially sliding elements consisting of the valve cone and valve stem, screwably mounted to the spring loaded abutment unit, terminating in a square plate, 15 14, is prevented from backing out of the rear of the body, when the ring nut, 16, with attached thermostatic unit is removed; its retention is accomplished by indenting the back end of the slide 20 grooves, 15, for the corners of said plate, which grooves also prevent rotation of said abutment unit. These indentures are indicated by 15'.

It should be further noted that while said ring nut is tightened in position with its retained bellows mechanism, that the center of said abutment plate is solidly back-stopped by the central projecting circle of the bellows joint, and that the thermostatic unit, consisting of the flanged bellows capsule, 17, with appending expansion bulb, is readily detached from the valve body, by 30 the unscrewing of said ring nut.

From the foregoing it should be apparent that by the substitution of a blind screw-cap, (not shown), for this detachable unit, screwed on in place thereof, to seal the body, and back-stop 35 said abutment, the valve may be manually operated; not only in so far as modulation of the heating fluid is concerned; but by turning the handle to the extreme right, to the indicated off position, the valve may be tightly closed through 40 the medium of the coarse left handed threaded joint between the interior of the valve cone and threaded head 5, of said spring loaded abutment. Under this condition the valve cone will be firmly seated under the resilience of the loading 45 spring, acting against the steam pressure so that it is possible to change external parts with the steam on. This hand operation is of advantage for installations in buildings during completion, also providing temporary means for manual 50 operation in case of injury to thermostatic unit; which may be supplied as an interchangeable part.

The loading spring, 18, is given a permanent tension, sufficient to firmly seat the valve, by 55 means of screw, 19, only yielding after seating the valve to permit further expansion of the liquid without injury.

The expansion bulb, B, should be of a suitable length to give the required capacity for the expansion liquid chosen, after an account is taken 60 of the amount of the expansion displacement desired per degree of bulb temperature change. The chosen liquid should have a high expansive coefficient and should also have a high boiling 65 point, preferably above the highest working temperature of the heating fluid it is intended to control. I have found kerosene satisfactory for this purpose.

The diameter of the expansion bulb has been 70 so designed as to just pass through union nut, 16, so that the whole thermostatic unit, including bellows chamber, expansion bulb and connecting tube, can be most conveniently liquid filled, sealed, tested and calibrated at the factory 75 before the nut is slipped into place over them,

regardless of the length of the connecting tube. Round anchor disks, 20 and 20', are soldered or otherwise secured to the ends, respectively, of expansion bulb, B, and bellows capsule, 17, back of which one or more flexible turns of their connecting tubing are made before the tubing is led off to the other unit connected thereby, thus affording a resilient section between the soldered connections to said units and the lead-off stretch, materially reducing the liability of strain on 10 their soldered in connecting ends during the process of manufacture, distribution and assembly.

Furthermore, disk, 20', on the bellows capsule performs the function of back-retainer for the draft stack, 2, on certain types of installation 15 such as are shown by Figs. 1, 9 and 12.

The draft stack is preferably made in the form of a vertical tube, which may be of either insulating material or metal. This tube is capped at both ends by openly perforated covers, 21 and 20 21', affording a free circulation of air. The cover at the valve end of the stack is deeply notched, semi-circularly and of two diameters at the opposite sides to match the difference in diameter at the opposite ends of capsule, 17, onto which it 25 is saddled. This deep cover overlaps the end of the stack to which it is secured by four screws, indicated by 22. The other end of the stack may be rigidly strapped by screw clamps, 23, to the supply pipe, as in Figs. 9 and 11, or to the wall, 30 as in Fig. 12.

The expansion bulb is inserted in the stack prior to the placing of the cover and fastening and it may be positioned therein in any suitable manner, such as by the spacing screws indicated 35 by 24.

In the installation, shown by Fig. 11, the bulb is positioned toward one side of the stack so as to overlap capsule, 17, the latter being inserted through a hole punched in the stack cover. 40 There is shown in this figure, above the dotted in valve handle, an extension handle shaft, 9', having a squared key socket adapted to fit the upturned squared shaft end of the valve, which is exposed when its insulating handle knob is 45 removed to make such extension for covered radiators.

Referring to the close connected universal swivel valve coupling, shown in detail by Figs. 4, 5, 6, and 13, a girdling groove, 25, is machined 50 around the short neck, 26', of the hollow, L shaped casting, 26. The depth of this groove is approximately half the diameter of its wire lock ring, 27. This ring is wound from heavy wire with the abutting ends of its open gap 27', nearly 55 touching. While a spring, or multi-section ring may be used for this purpose, I prefer to use the notched, one piece ring shown, having the two hinge notches, 27'', spaced about one third the diameter of its circle from each other and 60 from the opening gap. This ring is initially formed and sized to snugly fit said groove. The ring so formed may be diagonally forced inside the nut and its expansion groove, 28', within the back of the ring nut. Said nut containing 65 the ring is then forced back over the beveled end of said short neck piece, which operation wedges the ring open and outward into said expansion groove in the nut, yielding at said notch hinges, where the metal bends sharply without otherwise deforming the ring, so that when the nut and ring are back in permanent position over said neck the two outward bent ends of the ring are 70 easily bent back, one at a time, in to a true circle, snugly seated in the anchor groove of the neck 75

piece by means of a punch pin inserted through hole, 28', in one side of the nut. When the nut is tightened onto its co-joining thread of body, opposite which it is positioned, the inward flare 5 of the inner gripping gland of said nut bearing on the ring, tends to clamp the ring down into its anchor groove, the more, as it is tightened.

The temperature indicating pointer, 29, consists of a flat punching, journaled on the handle 10 shaft and firmly clamped in any desired radial position in front of the temperature plate, 11, by means of the lock nuts, 12 and 12'.

The temperature plate may also be set in any desired radial position by loosening the lock 15 nuts, which hold its marginal portion in firm spring contact with the corresponding face of the bonnet. A stop lug 30, for the pointer, formed from the temperature plate by bent up tongue, 11', from its outer edge, is provided.

20 An enlarged modification of the valve cone is shown by Fig. 8, which is cheaper to manufacture. It is constructed by press drawing a cone shell body, V', from fairly heavy metal. The outer end of the cylindrical skirt of which is sheared off with a uniform helix spiral of the same pitch as that of the threaded head, 5', which it is to match and works within it, then this helix edge is forcibly curled inwards so as to form a single 25 thread V', over a hardened threaded steel mandrel, formed to fit and fill said shell but having the thread of its outermost end symmetrically cut away in to that point lying within the edge of the shell where it is to act as the spiral forming-edge. After this inward bent thread is 30 formed the mandrel is unscrewed from the shell; and the valve stem, 8, may be fixed into the apex of the cone in any suitable manner.

While the bellows capsule, 17, may be formed of any suitable metal, I prefer to construct it of 40 a stainless steel of the lowest heat conductivity.

I have shown the bellows push rod as constructed of insulating material but it may be constructed of metal and soldered to the rear end of the bellows.

45 I prefer to construct the valve cone of a suitable stainless steel, well hardened and to have the edge of the valve seat slightly rounded.

While the valve seat has been shown as formed directly in the brass partition of the body, it is 50 obvious that an interchangeable threaded ring seat of bronze, Monel metal or stainless steel may be used, and renewed by way of access of the removable bonnet.

55 From the construction described it will be noticed that the valve head V is mounted on a carrier which, in the present form of the device chosen to illustrate the principle involved, may be said to include the stem or screw 19, the abutment plate 14, the adjusting head or sliding element 5 and the spring 18, though not limited to these elements.

I claim:

1. A temperature regulating radiator valve 65 comprising a valve body having inlet and outlet openings, a partition within the valve body separating said openings, said partition being apertured to provide a valve seat, a valve head, a carrier therefor in relation to which the valve head is relatively adjustable whereby the valve 70 head may be moved toward or away from the valve seat while the carrier remains at rest, means for manual adjustment of the relative position of the head with respect to the carrier, a rigid stop limiting movement of the valve head

carrier away from the valve seat to enable the valve head to be tightly forced on to the valve seat upon manual adjustment of the valve head relative to said carrier and towards said seat, and thermally responsive means acting on said valve carrier to move it away from said stop and urge the valve head onto its seat independently of said manually adjustable means, said rigid stop permitting manual closure of the valve independently of the thermally responsive means. 10

2. A temperature regulating radiator valve comprising a valve body having inlet and outlet openings, a partition within the valve body separating said openings, said partition being apertured to provide a valve seat, a valve head, a carrier therefor in relation to which the valve head is relatively adjustable whereby the valve head may be moved toward or away from the valve seat while the carrier remains at rest, resilient means tending to move the valve away from its seat 15 to open position, a rigid stop limiting the movement of the valve head carrier away from the seat under the action of said resilient means, said stop also enabling the valve head to be tightly forced onto the valve seat upon manual adjustment of the valve head relative to said carrier and toward the seat, means for manual adjustment of the relative position of the head with respect to the carrier, and thermally responsive means acting on said valve carrier to move it 20 and the valve head against the action of said resilient means toward the valve seat, said rigid stop permitting manual closure of the valve independently of the thermally responsive means. 25

3. A temperature regulating radiator valve comprising a valve body having inlet and outlet openings, a partition within the valve body separating said openings, said partition being apertured to provide a valve seat, a valve head, a carrier therefor comprising a stem having an abutment, an element slidably mounted on said stem, and resilient means for urging said element against said abutment, said valve head being connected with and supported by said element and being relatively adjustable with respect thereto 40 whereby the valve head may be moved toward or away from the valve seat while said element remains at rest, means for manual adjustment of the relative position of the head with respect to said element, and thermally responsive means 45 acting on said stem to control movement of the valve head toward or away from the valve seat while the head remains in fixed relation to said element, said resilient means permitting continued movement of said thermally responsive means 50 in a valve closing direction after the valve head reaches its seat. 55

4. A temperature regulating radiator valve comprising a valve body having inlet and outlet openings, a partition within the valve body separating said openings, said partition being apertured to provide a valve seat, a valve head, a carrier therefor comprising a stem having spaced abutments, one of said abutments having engagement with the valve body to mount said valve head carrier in axial alignment with said aperture and permitting axial movement only of said carrier, a screw threaded element slidably mounted on said stem, and resilient means disposed between the element and the abutment 65 engaging the valve body to urge the element against the other abutment, said valve head being supported by said element and engaging with the screw threads whereby rotation of the valve head 70 will cause its movement toward or away from the 75

- valve seat while said element remains at rest, means for manually effecting rotation of said valve head relative to the non-rotating element of said carrier, and thermally responsive means 5 acting on said stem to control movement of the valve head toward or away from the valve seat while the head remains in fixed relation to said element, said resilient means permitting continued movement of said thermally responsive 10 means in a valve closing direction after the valve head reaches its seat.
5. A temperature regulating radiator valve comprising a valve body having inlet and outlet openings, a partition within the valve body separating said openings, said partition being apertured to provide a valve seat, said valve body also having an opening opposing said aperture, a valve head, a carrier therefor in relation to which the valve head is adjustable whereby the valve 15 head may be moved toward or away from the valve seat while the carrier remains at rest, means for manual adjustment of the relative position of the head with respect to the carrier, and a detachable closure member for said last named opening providing a back stop for said carrier whereby the valve head upon adjustment relative to the carrier may be moved away from said closure member and toward its seat and be forced tightly on its seat.
- 20 6. A temperature regulating radiator valve comprising a valve body having inlet and outlet openings, a partition within the valve body separating said openings, said partition being apertured to provide a valve seat, said valve body also having an opening opposing said aperture, a valve head, a carrier therefor in relation to which the valve head is adjustable whereby the valve 25 head may be moved toward or away from the valve seat while the carrier remains at rest, means for manual adjustment of the relative position of the head with respect to the carrier, and a detachable closure member for said last named opening providing a back stop for said carrier whereby the valve head upon adjustment relative to the carrier may be moved away from said closure member and toward its seat and be forced tightly on its seat.
- 30 7. A temperature regulating radiator valve comprising a valve body having inlet and outlet openings, a partition within the valve body separating said openings, said partition being apertured to provide a valve seat, said valve body also having an opening opposing said aperture, a valve head, a carrier therefor in relation to which the valve head is adjustable whereby the valve 35 head may be moved toward or away from the valve seat while the carrier remains at rest, means for manual adjustment of the relative position of the head with respect to the carrier, and a detachable closure member for said last named opening providing a back stop for said carrier whereby the valve head upon adjustment relative to the carrier may be moved away from said closure member and toward its seat and be forced tightly on its seat, said closure member comprising thermally responsive means acting on 40 said valve carrier through said opening to control movement of the valve carrier and the valve head toward or away from the valve seat while the valve head remains in fixed relation to the carrier.
- 45 8. A temperature regulating radiator valve comprising a valve body having inlet and outlet openings, a partition within the valve body separating said openings, said partition being apertured to provide a valve seat, a valve head, a carrier therefor in relation to which the valve head is adjustable whereby the valve head may be moved toward or away from the valve seat while the carrier remains at rest, said valve head having 50 a projection extending through said aperture, manually operable means engaging with said projection to effect adjustment of the valve head relative to the carrier, and stop means limiting movement of the carrier away from the valve seat upon adjustment of the valve head relative to the carrier in a direction against the valve seat, said stop means resisting the reactive thrust exerted by said carrier when the valve head is forced tightly on its seat.
- 55 9. The combination with a temperature regulating radiator valve comprising a valve body having a fluid passageway therethrough, a movable valve head for restricting said passageway, a movable member subjected to fluid pressure for actuating said valve, and a casing enclosing the movable member and extending horizontally from the valve body, the interior of said casing forming a wall of the pressure chamber surrounding the movable member and the exterior of said casing providing a supporting surface; of a bulb for supplying fluid pressure to said chamber in proportion to temperature variations and a stack engaging with and carrying said bulb, said stack having horizontally aligned openings of a size to receive therein said casing whereby the casing serves as a projecting stem from which the stack and bulb are suspended.
- 60 10. A temperature regulating radiator valve comprising a valve body having inlet and outlet openings, a partition within the valve body separating said openings, said partition being apertured to provide a valve seat, a movable valve head for cooperating with said valve seat, a valve head carrier with which the valve head has adjustable interengagement, means for manually adjusting the valve head on the carrier, and rigid means for maintaining the carrier at a fixed distance from the valve seat so that the valve head can be moved relative to the carrier and tightly on its seat.

EDWARD S. HALSEY.
